No. 830,792.

PATENTED SEPT. 11, 1906.

P. KÜHNE.
CORNER BEAD.
APPLICATION FILED JUNE 12, 1906.

UNITED STATES PATENT OFFICE.

PAUL KÜHNE, OF NEW YORK, N. Y.

CORNER-BEAD.

No. 830,792.

Specification of Letters Patent.

Patented Sept. 11, 1906.

Application filed June 12, 1906, Serial No. 321,383.

To all whom it may concern:

Be it known that I, PAUL KÜHNE, a citizen of the United States, residing in New York, in the borough of Brooklyn, county of Kings, 5 and State of New York, have invented certain new and useful Improvements in Corner-Beads, of which the following is a specification.

This invention relates to an improved corner-bead for protecting the edges of plastered walls at corners and other exposed portions of the same; and the invention consists of a corner-bead which is made of sheet metal with a rolled-up bead at the edge and wings 15 bent up in opposite direction to each other from said bead, said wings being provided with bent-up edge flanges and with holes for the nails by which the wings are attached to the corner of the wall to be plastered.

20 The invention consists, further, of a device for connecting the ends of two adjacent corner-beads so that pieces of any length can be used, which connecting device will be fully described and claimed hereinafter.

25 In the accompanying drawings, Figure 1 represents a perspective view of my improved corner-bead, showing it as attached to the corner of a wall before the plaster coating is applied thereto. Fig. 2 is a horizontal section on line 2 2, Fig. 1. Fig. 3 is a side elevation of the corner-bead after the same is cut into shape and before the wings are bent up. Fig. 4 is an end elevation of Fig. 3. Figs. 5 and 6 are horizontal sections, respectively, 30 on lines 5 5 and 6 6, Fig. 3. Fig. 7 is a detail perspective view of the connecting device between two adjacent sections of corner-beads, and Fig. 8 is a portion of the improved corner-bead bent so as to be used for curved 35 corner portions of the wall.

40 Similar letters of reference indicate corresponding parts in the several figures of the drawings.

Referring to the drawings, *a* represents the 45 rolled-up edge bead, and *b b'* the wings, of my improved corner-bead. The wings are bent up approximately at an angle of sixty degrees to each other at opposite sides of the bead. The corner-beads are made from flat 50 strips of sheet metal of any length, which are rolled up at one edge so as to form the bead *a* and which are then cut in a suitable press by means of tapering knives transversely across the body of the strip, so as to form tapering 55 wings *b b'* and tapering flanges *b''* along the edges of the wings *b b'*, as shown in Figs. 1

and 3. Simultaneously with the cutting of the wings nail-openings *e* are formed in the wings *b b'* by means of suitable punches or dies, which, like the knives, are arranged in 60 the press. The wings *b b'* are then bent in opposite direction to each other approximately at an angle of about sixty degrees from the bead and placed in position on the corner of the wall and attached thereto by 65 driving nails through the nail-openings *e* into the wall alternately at one side of the corner and then at the other side of the corner of the wall, and so on, as shown in Fig. 1. The plaster covering is then applied over the wall, 70 the corner-bead, and its wings, so as to be entirely embedded therein, as shown in Fig. 2.

As the sections of the corner-beads are made in any length desired, according to the various lengths of the sheet-metal blanks, it 75 is necessary to connect them at their adjacent ends by a suitable connecting device. This connecting device is formed of a short piece *f* of sheet metal, which is bent into a hollow bead *f'* along one edge, which is 80 clenched, so as to retain a coupling-wire *f''* in position therein. The slightly-curved end of the piece *f* is then inserted into the open ends of the beads *a* and curled up at the inside of the same, the bead *f'* and the wire *f''* being 85 retained at the outside of the bead *a*, as shown in Figs. 1 and 7, and locked in position by means of a U-shaped wire staple *f'''*, which is passed through holes *f''* in the adjacent wings *b b'* and intertwined with the ends of 90 the wire *f''*, as shown in Fig. 1, so as to hold the adjacent ends of the beads *a* of two sections or lengths of corner-beads permanently together. Any other connecting device may be used, as I do not desire to confine myself 95 to the special construction shown.

My improved corner-bead has the advantage of great cheapness, as the same can be made up from odd lengths or waste strips of sheet metal which are obtained in the manufacture of sheet metal. It has also the advantage that the corner-beads are reliably held on the corner of the wall by the fastening-nails and by the plaster covering for which the wings, with their edge flanges, 100 form anchors, the beads protecting the edge of the plastered corners of the wall. Another advantage is that corner-beads of any length can be made up by means of the connecting device, and, lastly, that the corner-beads can be bent to any shape or curve 105 without interfering with their construction 110

or strength, as required by the curved edges of the walls to be plastered.

Having thus described my invention, I claim as new and desire to secure by Letters 5 Patent—

1. A corner-bead consisting of an integral piece of sheet metal having a rolled-up edge, and wings bent alternately in opposite direction to each other from said bead, said wings 10 being provided with tapering flanges at their sides and with holes for inserting the fastening-nails.

2. A corner-bead consisting of an integral piece of sheet metal having a rolled-up edge, 15 and wings bent alternately in opposite direction to each other from said bead, said wings being slightly tapering from their inner toward their outer ends and provided with tapering side flanges and nail-holes for the fastening-nails.

3. The combination, with two adjacent lengths or sections of corner-beads provided with rolled-up edges, and wings bent alternately in opposite direction to each other

from said rolled-up edges, of a connecting device between the adjacent ends of the corner-bead sections.

4. The combination, with two adjacent lengths or sections of corner-beads provided with rolled-up edges, and wings bent alternately in opposite direction to each other from said edges, of a connecting device between the adjacent ends of the corner-bead sections, said connecting device consisting of a curled piece of sheet metal provided with a 30 bead at one edge, a connecting-wire in said bead, and a wire staple passing through holes in the adjacent wings of the corner-bead sections, said staple being intertwined with the ends of the wire for locking the sections together.

In testimony that I claim the foregoing as my invention I have signed my name in presence of two subscribing witnesses.

PAUL KÜHNE.

Witnesses:

PAUL GOEPEL,

HENRY J. SUHRBIER.
